FOOD CART

Stuart I. Freedman, Los Angeles, Calif., assignor to Walter Kidde & Company, Inc., Clifton, N.J.

Filed July 9, 1970, Ser. No. 23,890

Term of patent 14 years

Int. Cl. D12—02

U.S. Cl. D14—3

Fig. 1.

Fig. 2.

Fig. 4.

Fig. 3.

Fig. 5.

FIG. 1 is a perspective view of the food cart.
FIG. 2 is a top view of the same.

FIG. 3 is an end view of the same.

FIG. 4 is a bottom view of the same.

FIG. 5 is a perspective view of a modified form of the same.

The cart illustrated in FIG. 1 and the modified cart illustrated in FIG. 5 are each symmetrical in that both end portions are the same and both front and rear portions are the same.

I claim:

The ornamental design for a food cart, as shown and described.
